US00D510739S

(12) **United States Design Patent** (10) Patent No.: **US D510,739 S**
Jones et al. (45) Date of Patent: **** Oct. 18, 2005**

(54) **COMPUTER INTERFACE**

(75) Inventors: **Andrew Jones**, Roslindale, MA (US); **Jennifer Linnane**, Melrose, MA (US); **Daniel J. Reilly**, Jamaica Plain, MA (US); **Ryan M. McManus**, Cambridge, MA (US)

(73) Assignee: **SensAble Technologies, Inc.**, Woburn, MA (US)

(**) Term: **14 Years**

(21) Appl. No.: **29/192,801**

(22) Filed: **Oct. 30, 2003**

(51) LOC (8) Cl. **14-02**

(52) U.S. Cl. **D14/411**

(57) **CLAIM**

The ornamental design for a computer interface, as shown and described.

DESCRIPTION

FIG. 1 is a front perspective view of a computer interface showing our new design;

FIG. 2 is a side elevation view of the interface;

FIG. 3 is a front elevation view of the interface;

FIG. 4 is a top plan view of the interface;

FIG. 5 is a rear perspective view of the interface; and,

FIG. 6 is a rear perspective view of the interface with the stylus repositioned.

The broken lines in the drawings are for illustrative purposes only and form no part of the claimed design.
